UNITED STATES PATENT OFFICE.

JAMES WILLIAM BIGHAM AND WILLIAM JULIUS BARKER, OF JACKSONVILLE, FLORIDA.

SANITARY PILLOW-COVERING.

1,275,205.

Specification of Letters Patent. Patented Aug. 13, 1918.

Application filed September 10, 1917. Serial No. 190,536.

To all whom it may concern:

Be it known that we, JAMES W. BIGHAM and WILLIAM J. BARKER, citizens of the United States, residing at Jacksonville, in the county of Duval and State of Florida, have invented certain new and useful Improvements in Sanitary Pillow-Coverings, of which the following is a specification, reference being had therein to the accompanying drawing.

This invention relates to the art of sanitation and more particularly to auxiliary covers for pillows used on beds in Pullman cars and other places where a head rest is used.

The invention has for one of its objects to provide an absorbent auxiliary cover for the pillow proper.

A further object is to construct the auxiliary covering of a soft waterproof paper, or of a soft paper provided with a coating of paraffin on one side.

A further object is to construct the auxiliary pillow cover, in such a manner, that the same can be folded upon itself on the end of the pillow and its sides overlapped on the longitudinal edges of the pillow, thereby allowing the cover to be easily placed over the pillow and at the same time providing a structure, wherein a paper material may be used.

A further object is to provide an auxiliary cover for a pillow to prevent the perspiration or oils used upon the hair of the sleeper from penetrating the pillow, often causing disease to be transmitted to others and also imparting odors that are objectionable to other occupants of the bed.

A further object is to construct the auxiliary cover that when one side of the pillow has been used, the used side of the auxiliary cover may be detached from the unused side and the pillow turned over, so that the pillow will present the clean side of the pillow case with the unused side of the auxiliary cover to the next occupant of the bed.

With the above and other objects in view which will appear as the description proceeds, the invention resides in the details of construction and combination and arrangement of parts hereinafter described and claimed, it being understood that changes in the precise embodiment of the invention herein described can be made within the scope of what is claimed with-

out departing from the spirit of the invention.

In the drawings:

Figure 1 is a perspective view of the pillow having the auxiliary cover thereon, showing the same in position to be placed in the pillow casing.

Fig. 2 is a longitudinal sectional view through a pillow, showing the auxiliary pillow cover in place.

Fig. 3 is a sectional view on line 3-3 of Fig. 2, showing the overlapping sides of the auxiliary cover.

Fig. 4 is a perspective view of the auxiliary covering, showing the same before being folded over the pillow.

Fig. 5 is a fragmentary sectional view of a portion of the auxiliary covering, showing the side next to the pillow coated with paraffin or the like.

Fig. 6 is a perspective view of another form of the invention, showing the auxiliary covering made bag shaped, but having its three sides perforated.

Fig. 7 is a top plan view of a pillow, showing parts broken away to show the bag shaped auxiliary casing or covering.

Referring to the drawing 1 designates a pillow of the usual construction comprising the ticking 2, which is provided with a filling 3 of hair, feathers or other material. Between the pillow casing 4, which is of the usual construction and the pillow 1 is an auxiliary pillow covering 5, which comprises the enlarged portions 6 and 7 adapted to overlie and register with the top and bottom surfaces of the pillow. The sections 6 and 7 are provided with portions 8 and 9, which, when the auxiliary covering is disposed between the pillow and the pillow casing, overlap as clearly shown in Figs. 1, 2, and 3. The sanitary auxiliary covering on either side, substantially intermediate its length is provided with notches or cutaway portions 10 so that the overlapping members 8 and 9 will readily overlap when the auxiliary covering is in place. These cutaway portions also form means or starting points for tearing the sections apart when it is desired to remove one of the sections 6 and 7 without removing the pillow from the casing 4. Thus it is obvious, that one side of the pillow may be used and the perspiration or oils from the hair will be prevented from reaching the pillow ticking and consequently

110

from the filling therein. It will also be seen, that the used side of the auxiliary covering may be torn from the clean and unused side, without removing the pillow casing and the 5 pillow turned over, thereby presenting a fresh side of the casing for the next occupant of the bed or user of the pillow, the unused side of the auxiliary covering will also be in position for use. It is the object 10 to construct the auxiliary covering from a cheap absorbent material such as paper of a soft texture and to provide it, if desired, with a paraffin coating on its inner surface as shown at 11, in Fig. 5, or the material 15 may be of the conventional soft texture waterproof type commonly found upon the market.

To place the pillow in the casing, the pillow is disposed upon the section 6 of the 20 auxiliary covering, then the section 7 is folded over the top of the pillow, after which the members 8 are folded upwardly and the members 9 are folded downwardly over the members 8. The pillow being 25 completely covered with a waterproof auxiliary covering it is then in condition to be placed in the pillow casing 4. It will be seen that by constructing the auxiliary covering in this way, that a close fit on the pillow can 30 be obtained.

In Figs. 6 and 7 it will be seen that the auxiliary casing 5^a is made bag shaped, that is of the shape of the pillow casing 4, but sufficiently large so that the pillow 1 can be 35 easily placed therein without tearing the auxiliary casing. This casing 5^a upon its three side edges 5^b is provided with perforations 12 so that the used side of the casing may be removed, if desired and the unused 40 side left in the pillow.

The invention having been set forth, what is claimed as new and useful is:—

1. An auxiliary pillow covering disposed

between the ticking of a pillow and the pillow casing, comprising an elongated member, adapted to be bent upon itself to form top and bottom sections to register with the top and bottom surfaces of a pillow and members carried by the sides of the sections adapted to overlap each other. 45 50

2. An auxiliary pillow covering disposed between the ticking of a pillow and the pillow casing, comprising an elongated member having cutaway notches on either side thereof, said member being adapted to be bent upon itself at said notches, thereby forming top and bottom sections adapted to register with the top and bottom surfaces of the pillow, said sections having overlapping integral members which when overlapped in 55 60 conjunction with the sections form a complete auxiliary covering for the pillow.

3. An auxiliary pillow covering disposed between the ticking of a pillow and the pillow casing, comprising an elongated member having means central of its length upon which the covering is folded thereby forming top and bottom sections, said sections registering with the top and lower surfaces of the pillow and means centrally located 65 70 upon said auxiliary covering whereby one section of said covering may be easily torn from the other without removing the pillow and other section from the pillow casing.

4. An auxiliary pillow covering disposed 75 between the ticking of a pillow and the pillow casing, comprising a covering having sections for engaging and covering both sides of the pillow and provided with means whereby the sections may be easily separated. 80

In testimony whereof we hereunto affix our signatures.

JAMES WILLIAM BIGHAM.
WILLIAM JULIUS BARKER.
